DESIGN FOR LIGHT DIFFUSING GLASS

William F. M. Hawe, Crafton, Pa., assignor to
Consolidated Lamp & Glass Company, Cora-
opolis, Pa., a corporation of Pennsylvania

Application March 21, 1939, Serial No. 83,728

Term of patent 14 years

To all whom it may concern:

Be it known that I, William F. M. Hawe, a citizen of the United States, residing at Crafton, in the county of Allegheny and State of Pennsylvania, have invented a new, original, and ornamental Design for Light Diffusing Glass, of which the following is a specification, reference being had to the accompanying drawing, forming part thereof.

Figure 1 is a top plan view of a segment of light diffusing glass showing my design;

Figures 2, 3, 4 and 5 are sectional views, taken respectively on the lines 2—2, 3—3, 4—4 and 5—5 of Fig. 1, looking in the direction of the arrows.

I claim:

The ornamental design for light diffusing glass as shown.

WILLIAM F. M. HAWE.
